UNITED STATES PATENT OFFICE.

WILLIAM CLIFTON HART, OF ADELAIDE, SOUTH AUSTRALIA, AUSTRALIA.

MEANS FOR FORMING LABELS AND THE LIKE ON WOODEN CONTAINERS AND THE LIKE.

Application filed August 2, 1926, Serial No. 126,623, and in Australia September 7, 1925.

This invention has for its object the formation of labels, designs, symbols and the like on wooden case ends or sides and/or wooden containers and the like and method 5 and means for applying same.

The invention relates to the formation of labels, symbols, designs and the like on wooden case ends or sides or wooden containers and the like by indenting the label or design 10 in the material of which the case or container is made, and at the same time colouring same in one or multi colours, by means of, preferably, a raised type high design made of suitable materials such as zinc plate brass or an 15 alloy. The design being so made and adjustable that its surfaces are coloured in one or more colours as desired, the colour or any number of them being imparted to the imprint of the design or label at one and the same operation. The depth of the imprint of the 20 design on the case end or container is so regulated, that any depth of imprint with the raised high type surfaces may be easily acquired as hereinafter described.

25 The essential features embodied in the invention are substantially as follows:—

(a) The arrangement of a cylinder carrying a design or label and disposing preferably above the said cylinder a further cylinder 30 having attached to its circumferential surface the ink or colour distributing device or devices for colouring the label or design situated on the lower cylinder, before the coloured imprint is given to case or container 35 ends.

(b) The use of colouring means of any suitable absorbent material such as felt, chamois or cloth and the like, which may be in the form of pads and which are adjustably 40 and detachably held to a cylinder disposed so that the said pads contact with the distributing pad on a cylinder disposed above the roller carrying the printing means, said cylinder or roller being the lowermost of the 45 set.

(c) The provision of means for obtaining any desired depth of imprint to the label or design on the wooden case or container ends by making the lower or printing cylinder 50 adjustable by suitable means such as springs to enable it to easily adapt itself to any unevenness of the article which it is desired to label

or imprint, and also the different sizes or depths of the various materials which are to be labelled, or the lower or printing cylinder 55 may be stationary, in which case the platform or table or portion thereof such as a floating panel over which the material passes when imprinting or labelling will be adjustable, so that the raising or lowering of this 60 platform or floating panel has the same effect as in lowering or raising the lower cylinder containing the design, that is, altering the depth of the label imprint and at the same time accommodating the cylinder to the thickness or depth of the article passed under it. 65

(d) Divisioning or dividing the colouring pads, attached to the upper cylinder, in order that multicolours may be imprinted at one and the same operation, instead of as is in 70 vogue at the present time, where say three colours are to be printed, and furthermore, the divisioning or zoning of these colour pads may be accomplished in any practical way in order to conform to those various portions of 75 the label or imprint desired to be variously coloured, for example, the contents of a case or container may be in two colours, the manufacturer's name in say three colours, and his place, street or city or State of manufacture 80 having a different colour for each word.

(e) Forming the wall of each cylinder with perforations in order that the colour pads may be fed by suitably designed receptacles situated inside the cylinder and having their 85 attachments to said colour pads passing through any of the perforations and affixed thereto by suitable means to give them more stability. An additional advantage of the perforations in the colour pad cylinder is that 90 the colouring pads may be more easily attached to the cylinder, and more readily adjustable if out of alignment with that portion of the lower cylinder label or design to be coloured. The colour pads of the upper cylinder and the label design of the lower one, may be attached to these cylinders by projections 95 passing from them through the perforations and fastened inside the cylinder by any suitable means.

In order to more readily understand the invention reference will now be made to the accompanying drawings in which:—

Figure 1 is a view in side elevation of a

machine constructed according to my invention.

Figure 2 is a rear view thereof.

Figure 3 is a view thereof from the feeding end.

Figure 4 is a plan view of the table with gears and rollers removed.

Figure 5 is a view of a roller showing method of attaching inking pads thereto.

10. Figure 6 is a view of an inking roller showing means for supplying the pads with ink.

Figure 7 is a detail view showing alternative means for allowing different thicknesses of material passing through the machine, and

15. Figure 8 is a view of the printing roller.

According to this invention a table 5 is supported upon legs 6 adapted for bolting or otherwise affixing to the floor or a suitable foundation.

20. The table 5 has vertical arms 7 mounted on bars 8 the whole being horizontally adjustable on the table 5 by providing slots 9 thereon, the adjustment being necessary to permit boards of various widths being fed to the 25 printing rollers.

The printing means comprises rollers 10, 11, 12 mounted on spindles carried in the supports 13, 14.

30. Mounted on the spindle 15 of the roller 11 is a toothed wheel 16, meshing with a pinion 17 on the spindle 18, said pinion 17 meshing with a toothed wheel 19 on the spindle 20, a pinion 21 meshing with the toothed wheel 19.

The spindle 22 of the pinion 21 carries a 35 roller 23 which is formed centrally of its length to receive a chain 24 which passes about a toothed wheel 25 at the feeding end of the machine.

The surface 5^a of the table 5 is provided 40 with a slot 26 in which the chain 24 moves and the table surface 5^a is cut away as at 27 to permit portion of the roller 23 to pass slightly above the surface of said table, whilst the chain 24 also projects slightly above the surface 5^a of said table.

45. The object of the chain 24 is to feed the boards to the printing means, and when said boards reach the said means the roller 23 carries them through the machine as the printing or embossing operation is being performed.

50. Co-axial with the pinion 17 is a pinion 28 retained and supported by a bracket 29, cast on or fitted to the support 13, the outer end of the spindle 18 carrying a toothed wheel 30 55 which is in mesh with a pinion 31 on the shaft of a motor 32 mounted on an extension 33 of the table 5 a leg 34 being adapted to support the extension.

The whole of the apparatus is operated by 60 the motor 32, the operation of which moves the toothed wheel 30 and pinion 28 on the spindle 18 the co-axial pinion 17 moving therewith and in turn moving the toothed wheels 16 and 19 and pinion 21 which causes

the chain feed device to move in the required direction, whilst a toothed wheel 16^a meshing with the toothed wheel 16 turns the toothed wheel 16^b on the spindle 16^c of the roller 12.

Disposed forwardly of the roller 11 is a buffer 35 which is in line with the vertical 70 arms 7 the said buffer being adapted to retain the boards 7^a in position preparatory to moving one at a time to the rollers, and as each board is carried forwardly by the chain 24 the remaining boards settle down by their 75 own weight when the next board is carried through and so on.

The roller 11 is the printing roller, the roller 10, the distributing roller, and the roller 12 the inking roller, and I will now describe the 80 inking roller 12.

This roller is a perforated cylinder carried on the spindle 16^c and is adapted to carry the supply of ink or like fluid in the different colours which ultimately form the design 85 which will be according to the requirements of the packer.

The colours are held in receptacles as 90 which are detachably and adjustably disposed inside the cylinder 12, a filling portion 37 being fitted to said receptacles and a non-return or ball valve 38 between the pad 39 and the receptacle 36, which is adapted to prevent the colour fluid passing to the inking 95 pad too rapidly, such ball valve acting as a regulating means.

The inking surface 40 may be composed of any suitable material such as chamois, felt and the like and is held in a curved plate 41 detachably and adjustably held to the cylinder 12 by means of plates 42 held to the cylinder 12 by means of bolts 43 which pass through the perforations 44 and it is preferred to make the plates adjustable by forming slots 45 therein in order to provide for 100 various sized inking pads.

The pads 40 having the necessary design thereon are saturated by colouring from the receptacles 36 and the design is then transferred from the said pads 40 to the distributing roller 10 which is partly surfaced with a resilient pad 46 which receives the design in colour from the said pad 40.

The resilient pad 46 picks up only a very thin film of ink or like material from the pads 40 and as the cylinder or roller 10 continues to revolve the colour is then imparted to the printing roller 11 carrying the particular design to be transferred to the boards 7^a as they 110 pass through the machine.

The design is preferably cut in metal and is of the type high variety so that a certain indentation is given the design on the boards with the colour set out in any manner suitable to the packer.

120. The designs on the printing roller 11 are preferably disposed between rings 47—48 which act also as a guide for the boards 7^a

and prevents them from wandering thereby ensuring the said boards being uniformly branded.

The distance between the rollers 10 and 11 5 may be adjusted by means of the screws as 48^a operated by the hand wheels as 49, and if necessary similar raising or lowering means may be used in connection with the distance between the roller 11 and the surface of the 10 table 5.

If necessary also the table may be mounted so that it will rise and fall according to the varying thicknesses of boards being used, and this could be obtained by providing a floating 15 panel 50 in the table top, said panel being retained by means of studs 51 surrounded by springs 52 which would permit the said panel 50 rising and falling as the boards passed between it and the printing roller 11.

20 In carrying the invention into practical effect, the boards 7^a are stacked between the arms 7 as shown in Figure 1.

Upon starting the motor 32 the gears 17—16—19—21—16^a and 16^b are operated together with the cylinders or rollers 10, 11, 12 25 and feeding chain 24.

The lowermost board is moved forwardly by means of the chain 24 until said board meets the printing roller 11 when said board, 30 during the printing operation, passes between said roller 11 and the roller 23.

As the printing proceeds the board passes out to the rear of the machine to be followed by the next board, the operation being continuous, for as one board moves forwardly the 35 next board drops down and passes to the printing roller 11.

The ink or colour containers or receptacles 36 will require replenishing from time to time

and this will necessitate stopping the machine, but if the colour containers 36 are of substantial proportions the replenishing operation need only be infrequently performed.

The design to be imparted to a board may be built up of a number of colour arrangements 45 to suit the taste of the packer and furthermore the said design may be divisioned so that any particular portion thereof may be in one colour and the other in another colour to form a contrast.

50 What I claim as my invention and desire to secure by Letters Patent is:—

1. In means for forming labels and the like on wooden containers and the like, a perforated cylinder for holding a colour inking device detachably and adjustably to the cylinder, said means consisting of a curved colour device formed to correspond to the radius of the cylinder, bolts extending through any selected group of perforations in said cylinder, 55 said bolts engaging slotted plates on the colour device, the ends of which plates distant from the slot are adapted to engage with the colour device substantially as described.

2. In means for forming labels and the like 60 on wooden containers and the like, a cylinder, an inking pad arranged on said cylinder, means for supplying colour liquid to said pad, said means comprising containers connected to the pad, said containers being disposed 65 within the cylinder, and a ball valve for controlling passage of liquid from the containers to said pad for the purposes specified.

70 Signed at Adelaide, State of South Australia, Australia, this twenty-fifth day of 75 June, 1926.

WILLIAM CLIFTON HART.
